PERMANENT AWNING

Samuel Morasca, Pittsburgh, Pa., assignor to Kool Vent
Metal Awning Corporation of America, a corporation of Pennsylvania

Application January 17, 1956, Serial No. 39,818

Term of patent 14 years

(Cl. D21—6)

Fig. 1 is a perspective view of a permanent awning embodying my design; and

Fig. 2 is a vertical sectional view taken in the plane of line II—II of Fig. 1 with structural parts omitted.

I claim:

The ornamental design for a permanent awning, as shown and described.
